UNITED STATES PATENT OFFICE.

GEORGE A. HEATH, OF GENEVA, FLORIDA.

OIL-CARRYING SHELL.

SPECIFICATION forming part of Letters Patent No. 379,161, dated March 6, 1888.

Application filed December 22, 1887. Serial No. 258,742. (No model.)

To all whom it may concern:

Be it known that I, GEORGE A. HEATH, a citizen of the United States of America, residing at Geneva, in the county of Orange and State of Florida, have invented certain new and useful Improvements in Oil-Carrying Shells; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 My invention relates to an improved oil cartridge or shell; and it consists in the novel construction and arrangement of the parts thereof, which will be more fully hereinafter described, and particularly pointed out in the 20 claims.

The object of my invention is to provide a cartridge or shell containing a charge of oil for quieting rough water, with a charge of powder or other explosive for propelling the 25 same from a gun or mortar, and also for spreading the oil. I attain this object by the construction illustrated in the accompanying drawing, which represents a longitudinal vertical section of my improved device.

30 A indicates the outer shell or casing, suitably constructed of metal, having a suitable partition-plate, B, upon one side of which a charge of powder, C, is placed and ignited by a percussion-cap, c, as shown. A similar cartridge or shell, D, is mounted in connection with the opposite side of the partition-plate B, and is also provided with a charge of powder, E, or other suitable explosive. Projecting 35 slightly through the partition-plate B into the charge of powder C, and into the explosive material within the shell D, is a fuse, F.

Surrounding the internal cartridge, D, a charge of oil, G, is carried within the compartment formed by the partition-plate B and the 45 point of said cartridge. In the construction of this cartridge, the partition-plate and internal cartridge, D, are placed within the outer shell, A, in such a manner as to leave a space between the butt of the cartridge and the said 50 partition-wall for the reception of a charge of

powder or other explosive C. The cap is then placed over the cartridge, as shown, it being understood that the oil will have first been placed within the outer shell, A. When this projectile is propelled from the gun or mortar, the charge of powder C ignites the fuse F, which in turn ignites the charge E and explodes that portion of the shell carrying the oil, which spreads it over the surface of the water.

It will be understood that the charge of powder C propels the cartridge, and the oil is not spread upon the surface of the water until the internal cartridge, D, is exploded, which will take place sometime after the explosion of the charge of powder C. By this means the best results can be obtained and the oil rendered more effective in its desired use. It will also be understood that any explosive material may be used and oil which gives the best results for the desired purpose.

Having thus described my invention, what I claim is—

1. The combination, with the outer shell or casing, the interior partition-plate having an 75 interiorly-arranged cartridge resting thereagainst and supported thereby, which contains an explosive material, a fuse extending through said plate and projecting into the explosive of the interiorly-arranged cartridge, a charge of 80 explosive material upon the opposite side of the partition-plate to propel the projectile entire, and an oil-reservoir surrounding the interiorly-arranged cartridge, the explosion of the said interior cartridge, caused by the ignition 85 of the fuse transmitting fire from the propelling charge of explosive, spreading the oil upon the water, substantially as described.

2. The combination of the outer main shell or casing, having an interior partition-plate 90 dividing the shell into two parts for carrying oil and a propulsive explosive, respectively, and an interiorly-arranged cartridge within the oil-chamber containing an explosive material and connected to the propulsive explosive by a fuse, substantially as described.

3. A device for discharging oil upon the sea or waters when agitated, consisting of a shell or receptacle provided with an interior partition dividing the same into an explosive and 100

oil chambers, and an explosive cartridge suspended in the oil-chamber independent of the main explosive chamber and connected with the latter chamber by a fuse, substantially as described.

4. An oil-containing shell for the purpose set forth, having a propelling explosive contained therein separate from the oil and car-

tridge within and surrounded by the oil and connected to the propelling explosive by a fuse, to

In testimony whereof I affix my signature in presence of two witnesses.

GEORGE A. HEATH.
